UNITED STATES PATENT OFFICE

GUIDO M. SACERDOTE, OF BAYSIDE, NEW YORK

SHEET HOLDER AND BOOKMARK

Application filed May 16, 1928. Serial No. 278,240.

This invention relates to improvements in bookmarking devices and more particularly refers to bookmarking devices of a novel and improved character which are adapted to hold the sheets of an open book flat against the cover preventing the possibility of their bulging and unfolding.

The primary object of this invention is to provide a new article of manufacture in the nature of a device adapted to be used as a bookmark and adapted at the same time to be used as a clamp or holder for the sheets of a book, preventing their bulging out or unfolding while the book is being read.

Another object of this invention is to provide a bookmark of a novel and improved character adapted to be secured onto the cover of a book and formed with yielding means adapted to clamp the sheets of a book against unfolding as they are gradually turned over by the reader.

A further object is to provide a bookmarking device and sheet holder comprising an expansible clip portion and an ornamental covering for the backing member thereof, forming an expansible clamping device which may be used as a bookmark and which can also be used as a means for holding the sheets of an open book flat against the cover, preventing their bulging out or unfolding.

Other objects and advantages of the present invention will more fully appear as the description proceeds and will be set forth and claimed in the appended claims.

Bookmarking devices generally consist of an ornamental flat piece of metal or ivory or leather or other suitable material, which is inserted between the sheets of a book in order to enable the reader to open the book at the proper place. A bookmark of the ordinary type therefore does not as a rule, fulfill any useful function while the book is being read, its function being limited to marking the place at which the book should be opened in order to continue its reading or in order to quickly locate some particular page in the book.

It is a common experience with book readers to be compelled to use both hands in holding a book open and more particularly in

holding the sheets flat against the cover of the book in order to prevent the sheets from moving or from bulging outwardly or from unfolding outright while a page of the book is being read. This happens as a rule with most new books, especially with books which are tightly bound and with books which have an abnormal thickness.

The tendency of turned over leaves in books to unfold is one of the most frequent sources of annoyance to readers, suitable means for preventing which, insofar as I know, have not heretofore been proposed.

The present invention has for its main object to provide as a new article of manufacture, a device adapted to firmly hold turned over sheets against the cover of a book, making it unnecessary for the reader to do any more than hold the book open with one hand. At the same time the device can also be used as a bookmark assisting in the opening of a book at the proper place, where the mark has been set.

In its simplest form my improved device essentially consists of a clip having two spreading substantially parallel jaws, said clip being larger than those merely designed for holding together a number of sheets; while in its preferred form, the device also comprises an ornamental backing carried by one of the clamping members serving to conceal the clip portion from view and providing means for making the device in an unlimited variety of designs and shapes, greatly enhancing its appearance.

Clips made from a single piece of wire bent to form two clamping members or jaws which normally lie in the same or adjoining planes and which can be spread apart to a considerable extent always remaining parallel to each other, have been described and claimed by me in a patent entitled Paper clips, issued to me April 1, 1930, No. 1,753,094.

Other devices of the same character can be used for the purposes of the present invention, it being unnecessary in the present case for the two clamping members to be normally lying in the same plane, this being one of the characteristics of some of the clips described in said patent.

Such a feature is necessary in a clip which is intended at times to connect only two sheets together, but in a device of the type to which this invention refers, the clamping action is practically always exerted to hold together a material thickness of papers, since the device is attached to the cover of the book which usually is considerably thicker than a number of sheets placed together.

10 My invention will be better understood by referring to the accompanying drawing in which:

15 Fig. 1 is a plan view of my device as applied onto the cover of a book;

18 Fig. 2 is a front end view in elevation, partly sectioned of the same;

22 Fig. 3 is a rear end view in elevation of the same;

25 Fig. 4 is an inverted plan view of a device embodying my invention with the inner covering of the outer clamping member partly removed;

28 Fig. 5 is a side view in elevation of the same attached to the back cover of a book;

32 Fig. 6 is a plan view of the device shown in Fig. 4, attached to the back cover of a book illustrating its manner of operation;

35 Fig. 7 is a front end view in elevation of the device in extended position.

38 Devices of the character described in my other patent above referred to are adapted to be used as paper clips only; and although I have found that if they are made of a size sufficiently large they can also be used for 42 clamping leaves of a book onto the cover, they do not in reality fulfill the requirements of articles of this kind, because it is customary in bookmarks to have some ornamentation or design of an attractive character both for decorative and identification purposes.

45 Bookmarks are generally classified as novelties suitable to be given as gifts and are in fact chiefly sold under this heading; and therefore the attractiveness of the device is its most important feature aside from its useful character which it must also possess.

50 My device therefore consists essentially of an ornamental backing member preferably in the form of a plate or medallion, and a clamping device such as a paper clip of the expandable type of a size sufficient to hold together a considerable number of sheets, such as may be found in a book of ordinary thickness, integral with or attached to said backing member.

55 Referring to the drawing, 10 designates the ornamental backing member or plate to the underside of which is attached one of the clamping members of the clip 11, which is substantially of the type described and claimed in my patent above referred to.

60 Said clip 11 is formed of a single piece of wire bent in the middle at 12 to form two laterally adjoining loop portions 13, 14, bent

65 rearwardly and transversely in opposite directions to form head tracts 15, 16, respectively, constituting the outer and inner members of the base or head of the clip.

70 Said two tracts are once more bent forwardly at points 17, 18, to form fingers or prongs 19, 20, which together constitute one of the clamping members of the clip preferably the clamping member which is attached to the backing member 10 as shown by means 75 of studs or rivets 19', 20', acting as anchoring means, or in any other suitable manner.

78 When the clamping member formed by center portion 12 and loop portions 13, 14 is forced away from the clamping member 80 formed by fingers or prongs 19, 20, the two head tracts diagonally cross each other, but the two clamping members of which the clip is composed will always remain substantially 85 parallel to each other. The capacity of the clip thus formed to spread a given quantity is mainly dependent upon the length of the head tracts 15, 16, which under normal conditions should not be made to cross at an angle of more than 45 to 60 degrees.

90 The clamping member which is attached to the underside of the plate 10 is preferably covered with a thickness of material 21 providing a substantially flat inner surface of contact for said member.

95 Said material preferably has a good frictional surface and consists of a piece of felt or leather or preferably metal having a rough surface.

100 The clamping member constituted by the prongs 19 and 20 are thus secured between the plate 10 and the cover plate 21, studs or rivets 19' and 20' holding the plates 10 and 21 together as illustrated more clearly in Figs. 1 and 4. As shown in Figs. 1 and 5 105 the cover plate 21 is substantially co-extensive in area with the plate 10 and extends from beyond the prongs 19 and 20 to the head tracts 15 and 16. Thus, the open clamping member constituted by the fingers or prongs 19 and 20 are joined together or held in fixed 110 relation by the plates 10 and 21 in order to prevent movement of these parts with respect to each other.

115 In Figs. 1, 3, 22 designates the cover of a book, with my improved device attached thereto, said device being preferably inserted over the cover and leaves abutting there against, at the lower end of the left side of the book when the book is open.

120 In this manner when the book is being read, as the pages are turned over one by one from the right towards the left, they are gradually inserted under the inner clamping member of the device and will be retained thereby against the possibility of bulging or unfolding.

125 In a similar manner the device may also be attached onto the back cover 22' of the book so as to hold the rear sheets 23 from

unfolding therefrom, as Figs. 5, 6, clearly show.

This may become necessary when the lecture of a book has so far advanced that the bulk of the sheets which have been turned over do not retain any tendency to turn back, while on the other hand, the remaining sheets tend to unfold from the back cover.

The insertion of new sheets under the inner clamping member is facilitated by pressing against the outer end of the central loop shaped finger formed by bending the wire at 12. In fact, by referring to Figs. 5, 6, it will be observed that the bent end 12 of said finger projects outwardly of the inner sheet of the book clamped thereby; therefore the edge of said sheet will acts as a fulcrum, causing the inner ends of loops 13, 14 to move slightly away from the surface of the sheet, when pressure is applied to tip 12.

It is also possible if desired to use two holders one attached to the front cover and one attached to the back cover, so that the sheets at both sides of the book may be held in their fully spread condition, while the book is being read.

It is thus seen that I provide an entirely new article of manufacture in the nature of an expandible clamp adapted to hold the leaves of an open book in their spread condition, which can also be used as a bookmark. The use as a bookmark follows as a natural consequence, because when a book is temporarily laid aside and closed, the clamping device will remain set in position holding the pages which have already been read, clamped against the cover; so that in order to turn the book to the proper page it is sufficient to turn the cover and the clamping device causes the sheets or leaves clamped thereto to open therewith. The device can also be used for other purposes if desired.

The expandible clamping portion of the device can be made to differ in its construction from that shown in the drawing without departing from the inventive idea; it is also obvious that the ornamental part of the back ing member may assume a practically unlimited number of forms or designs and may be made in a number of different materials.

The drawing will therefore be understood as being intended for illustrative purposes only and not in a limiting sense; I accordingly reserve myself the right to carry my invention into practice in all those ways and manners which may enter, fairly, into the scope of the appended claims.

I claim:

1. A device of the class described, comprising a clamping portion formed from a single piece of metallic wire bent to form two clamping members and an expandible head connecting said members, one of said clamping members being open at one end thereof and a plate member attached to the

inner side of said open clamping member, forming a substantially flat clamping surface therefor.

2. A device of the class described, comprising a clamping portion formed from a single piece of metallic wire bent to form open and closed clamping members, and an expandible head composed of two members crossing each other and each connecting one of the sides of one of said clamping members to the opposite side of the other; and a member attached to one of the surfaces of said open clamping member preventing twisting movement of the elements composing the same.

3. A device of the class described, comprising a clamping portion formed from a single piece of metallic wire bent to form open and closed clamping members, and an expandible head composed of two members crossing each other and each connecting one of the sides of one of said clamping members to the opposite side of the other, and a plate member attached to the inner surface of said open clamping member forming a substantially flat clamping surface therefor and preventing twisting movement of the elements composing the same.

4. A device of the class described, comprising a clamping portion formed from a single piece of metallic wire bent to form open and closed clamping members and an expandible head comprising two members crossing each other connecting said members, and two plate members abutting one against each of the surfaces of said open clamping member, retaining said clamping member therebetween.

5. A device of the class described, comprising a clamping portion formed from a single piece of metallic wire bent to form open and closed clamping members, and an expandible head composed of two members crossing each other and each connecting one of the sides of one of said clamping members to the opposite side of the other, and two plate members abutting one against each of the surfaces of said open clamping member, retaining said clamping member therebetween and preventing twisting movements of the elements composing the same.

6. In a device of the class described, comprising a clamping portion formed from a single piece of metallic wire bent to form open and closed clamping members, and an expandible head composed of two members crossing each other and each connecting one of the sides of one of said clamping members to the opposite side of the other, means maintaining the elements composing said open member in substantially the same plane, irrespective of the degree of expansion of said device.

7. A device of the class described, comprising a clamping portion formed from a single piece of metallic wire bent to form two

clamping members and an expansible head composed of two members crossing each other and each connecting one of the sides of one of said clamping members to the opposite side of the other, one of said clamping members having its free end formed with a rearwardly extending portion providing a finger tip rest, and a plate member attached to the inner surface of the other clamping member, forming a substantially flat clamping surface therefor.

8. A device of the class described, comprising a clamping portion formed from a single piece of metallic wire bent to form open and closed clamping members, and an expansible head composed of two members crossing each other and each connecting one of the sides of one of said clamping members to the opposite side of the other, said closed clamping member having its free end formed with a rearwardly extending portion providing a finger tip rest, and a plate member attached to the inner surface of the other clamping member, forming a substantially flat clamping surface therefor.

9. A device of the class described, comprising a clamping portion formed from a single piece of metallic wire bent to form open and closed clamping members, and an expansible head composed of two members crossing each other and each connecting one of the sides of one of said clamping members to the opposite side of the other, said closed clamping member having its free end formed with a rearwardly extending portion providing a finger tip rest, and two plate members abutting one against each of the surfaces of said open clamping member, preventing twisting movements of the elements composing the same.

10. A device of the class described, comprising a clamping portion formed from a single piece of metallic wire bent to form open and closed clamping members, and an expansible head composed of two members crossing each other and each connecting one of the sides of one of said clamping members to the opposite side of the other, the elements composing said open clamping member being held in fixed relation to each other.

11. A device of the class described, comprising a clamping portion formed from a single piece of metallic wire bent to form open and closed clamping members, and an expansible head composed of two members crossing each other and each connecting one of the sides of one of said clamping members to the opposite side of the other, and means for holding the elements of said open clamping member in fixed relation to each other.

12. A device of the class described, comprising a clamping portion formed from a single piece of metallic wire bent to form open and closed clamping members, and an expansible head composed of two members

crossing each other and each connecting one of the sides of one of said clamping members to the opposite side of the other, said closed clamping member having a rearwardly extending portion, and means for holding the elements of said open clamping member in fixed relation to each other.
